UNITED STATES PATENT OFFICE.

JOHN M. BAILEY, OF WAVERLY, VIRGINIA, AND PEMBROKE S. RICH, AND JOEL GARFIELD, OF WORCESTER, MASSACHUSETTS.

ENSILAGE-CUTTING MACHINE.

SPECIFICATION forming part of Letters Patent No. 341,309, dated May 4, 1886.

Application filed June 7, 1882. Renewed April 14, 1886. Serial No. 198,780. (No model.)

To all whom it may concern:

Be it known that we, JOHN M. BAILEY, of Waverly, in the county of Sussex and State of Virginia, and PEMBROKE S. RICH and JOEL GARFIELD, both of Worcester, in the county of Worcester and State of Massachusetts, as joint inventors, have invented a new and useful Improvement in Ensilage-Cutting Machines, of which the following is a specification.

10 Our invention relates to certain improvements in that class of cutting-machines in which the corn-stalks to be cut are fed between feed-rollers provided for the purpose and cut into short pieces by knives fastened

15 upon the arms of a revolving balance-wheel; and the novelty consists in the construction, arrangement, and adaptation of the parts, which will be more fully hereinafter set forth, and specifically pointed out in the claims.

20 In the accompanying drawings, in which similar letters of reference indicate like parts. Figure 1 represents a full top view of our whole machine. Fig. 2 represents a front or end view of the same. Fig. 3 represents a partial side view of the machine, showing one side of the head and the mechanism for communicating motion to the lower feed-roller. Fig. 4 is a sectional view taken lengthwise of the machine just outside of the hopper-head

25 B, and shows the manner of weighting the upper feed-roller. Fig. 5 represents the other side of the head of the hopper from Fig. 3, and shows the gearing communicating motion from the lower to the upper feed-roller. Fig. 6 is a partial view showing a section of one arm of the revolving balance-wheel, the revolving knife k, and the manner of bolting the knife k to the arm to secure the proper adjustment of the revolving knives.

30 A represents the main frame of the machine. C represents the hopper or trough into which the forage to be cut is placed.

B represents the castings which form the sides of the head or end of the trough, and to 45 which the feed-rolls, gearing, and stationary bed-knife are secured.

The corn or forage to be cut is fed between feed-rollers R' R². The feed-roller R² revolves in stationary boxes placed in the head-pieces 50 B B. The feed-roller R' revolves in boxes formed in levers l l on each side of the ma-

chine. Said levers l are pivoted to the head B at pivot o, allowing the roller R' to rise or fall in the arc of a circle having its center at the pivot o. The levers l l project upward 55 on each side of the feed-roller R', and support a cover, i, protecting the upper roller, R', and assisting to guide the corn or forage between the feed-rollers. The connecting guard-cover i can be attached rigidly to the levers l l, or a 60 flexible connection can be used to allow the feed-roller R' to vary its position to accommodate more or less depth of forage at one end of the rollers than at the other.

p is a shaft revolving in boxes secured to the 65 main frame. (See Fig. 1.)

P is a driving-pulley secured to the shaft p.

D is a large heavy balance-wheel mounted on the revolving shaft p. The balance-wheel D is provided with arms, as shown in Fig. 2, 70 three arms being there represented; but more or less may be used, as may be desired. Upon each arm a steel knife, k, is secured by bolts c c, and the knives k k, revolving with the arms of the balance-wheel, cut the corn- 75 stalks or forage into short sections as the corn-stalks or forage is fed over the bed-knife k' by means of the feed-rollers R' R².

k' is the stationary bed-knife, as shown in Figs. 1 and 2, against the edge of which the 80 revolving knives k shear off the forage as it is fed over said bed-knife by the feed-rollers. It is of great importance that the revolving cutter-knives k k should pass close up to the edge of the bed-knife k'. Any endwise play 85 of the shaft p would allow the revolving knives to spring away from the stationary bed-knife, and would interfere with the proper operation of the knives.

To avoid all endwise play of the shaft p, we 90 provide a set-screw, s, secured to the main frame A by a support, a', as shown in Fig. 3. The box b, in which the shaft p revolves, is adjusted on the frame by means of the set-screw s, and is held in position by the bolts 95 d. If the shoulder upon the shaft p or the end of the box b should wear, so as to allow any end-play to the shaft p, it can be easily tightened by turning up the set-screw s, and the revolving knives can be thus adjusted to the 100 bed-knife and easily and permanently kept in their true position to secure a good shearing

cut upon the edge of the stationary bed-knife k' . The knives k are each adjusted on the arms of the balance-wheel D by means of the bolts c and set-screws e , (see Figs. 2 and 6,) so that all the knives k can be perfectly adjusted to the bed-knife to secure a shearing cut when the balance-wheel revolves. Motion is communicated to the lower feed-roller, R^2 , by means of the dial-plate J , (see Fig. 3,) said dial being provided with cogs $j j$, into which the screw-gear S meshes. The screw-gear S is placed loosely upon the shaft p , and is driven by the clutch-sleeve c' , which is operated by a lever, d' . When the clutch-sleeve c' engages 15 the catch c^2 on the end of the screw-gear, the screw-gear revolves and the dial-plate J communicates motion to the feed-roller R^2 . Coarse or finer screws S are used, as it is desired to secure a longer or shorter cut upon the forage. 20 The screw S is made in halves, so that it can be removed and another replaced upon the revolving shaft p to alter the length of cut. By means of the handle d' the feed-motion can be instantly started or thrown out of 25 gear. Motion is communicated from the lower feed-roller, R^2 , to the upper feed-roller, R' , by means of the train of gears g^4 , g^3 , g^2 , g^1 upon the other side of the feed-rollers from the dial plate J , as shown in Fig. 5. 30 The upper feed-roller, R' , is designed to rise and fall as the amount of forage to be cut varies in depth. The position of the gear g^4 is fixed, as the shaft connecting it to the lower feed-roller revolves in fixed and stationary 35 boxes. The gears g^4 , g^3 , and g^2 are attached to a frame, $x x x$. A link, x' , connects the centers of the gears g^4 and g^3 . The gears g^3 and g^2 are free to rise and fall as the feed-roller R' is raised or lowered by the different depths 40 of forage passing between the feed-rollers; but the feed-gears g^4 , g^3 , g^2 , and g^1 will always retain their proper relative position to each other and follow the movable feed-roller R' , in whatever position it may be, allowing it to 45 rise and fall freely to accommodate any desired depth of forage to pass between the feed-rollers. Two frame-links, $x x x$, are used, one on each side of the feed-gears g^4 , g^3 , and g^2 , and short studs pass through the gears g^2 , g^3 , 50 connecting the frame-links and forming bearings upon which these gears revolve. The links x' on each side of the gears g^4 , g^3 are connected in a similar manner.

As shown in Fig. 1, the bevel-gear p' on the 55 shaft p meshes into the bevel-gear o' on the shaft o^2 . Both shafts p and o^2 turn in a box, $n n$, secured to the main frame.

It is a hand-crank attached to the shaft o^2 , and, if desired, the machine can be run by 60 hand for light work by it. The operator can turn the crank with his right hand, and the

short shaft o^2 and hand-crank I, as shown in Fig. 1, are placed in such a position in relation to the hopper that the operator can use his left hand to hold or adjust the forage to be run through the cutters, and this machine can, if desired, be conveniently used as a hand-machine for cutting any kind of forage.

By the above-described arrangement of the shafting and gears in our machine, the driving-pulley P can be attached either to the shaft p or to the shaft o^2 , in place of the hand-crank I. Thus the driving-belt can be applied to drive the machine in front or upon the side of the machine, and in whichever direction may be most convenient in actual operation, as the line of the pulleys, on the shafts p and o^2 are at right angles to each other.

We have shown and described a complete machine; but it will be understood that we 8c lay no claim to the combination, with a stationary knife on the throat of the feed-box, of a shaft carrying a fly-wheel provided with knives, the adjustable journal-box, and the screws to force said box against the hub of the 85 fly-wheel, whereby the knives carried by the latter are adjusted to take up wear.

Having thus described the nature and operation of our improved ensilage-machine, what we claim as new, and desire to secure by 90 Letters Patent, is—

1. In an ensilage-cutting machine, the combination, with the lower roller, R^2 , and the upper roller, R' , connected at one end by gears and a frame and link, as shown, the former roller having upon its opposite end a disk, J , with teeth j , of the removable and interchangeable worm S , hung loosely upon the shaft p , which carries the fly and cutter wheel, the clutch c' , and lever d' , whereby the condition of feed may 100 be regulated and the feed thrown into or out of action at will, as set forth.

2. In an ensilage-cutting machine as described, the combination of the lower roller, R^2 , its connections with the main shaft, and a 105 clutch mechanism for throwing it into or out of gear at will, of the upper roller, R' , hung movably in pivoted elbow-lever l , and having gear g' , the gear g^4 , rigid with the lower roller, R^2 , and connected with the gear g' by the gears 110 g^2 , g^3 , the frame $x x x$, and link x' , all arranged and operating as set forth.
